CLAIM

The ornamental design for a portable electronic device, as shown and described.

DESCRIPTION

FIG. 1 is an isometric view of a portable electronic device; FIG. 2 is a front view of the portable electronic device in FIG. 1; FIG. 3 is a left side view of the portable electronic device in FIG. 1; FIG. 4 is a right side view of the portable electronic device in FIG. 1; FIG. 5 is a back view of the portable electronic device in FIG. 1; FIG. 6 is a top view of the portable electronic device in FIG. 1; and, FIG. 7 is a bottom view of the portable electronic device in FIG. 1.

The broken lines shown in the figures that are immediately adjacent to the shaded areas and define unshaded regions represent the bounds of the claim. All other broken lines, including the features within broken line boundaries are directed to environment. The broken lines form no part of the claimed design.
